UNITED STATES PATENT OFFICE.

MAX LUHN, OF BARMEN, GERMANY.

DEVICE FOR PURIFYING THE STEAM IN STEAM-GENERATORS.

1,044,208.

Specification of Letters Patent. Patented Nov. 12, 1912.

Application filed May 16, 1912. Serial No. 697,699.

To all whom it may concern:

Be it known that I, MAX LUHN, a citizen of the German Empire, residing at Barmen, Germany, have invented certain new and 5 useful Improvements in Devices for Purifying the Steam in Steam-Generators, of which the following is a specification.

In steam boiler construction one of the principles is to increase the evaporation 10 without increasing the evaporating surfaces, that is, to generate in as small a space as possible as large a quantity of steam as possible. Consequently engineers have proceeded to increase the speed of circulation 15 of the water. The result of this is, that no dry steam exists in the steam-space of the steam generator, for when the speed of circulation in the steam generator is great, the greater part of the masses of water mixed 20 with the steam are very powerfully expelled into the steam-space of the top drum, for example, from the pipes in which the circulating water is rising. In the steam-space the steam bubbles burst and the water ex- 25 pelled upward with the steam is thrown with great force against the walls of the drum, a portion of the water being converted into fine mist or drizzle.

Now even in the case of steam boilers 30 which are fed with purified water, it cannot be altogether avoided that the water becomes turbid on account of solid substances, principally of a mineral nature, liberated in the boiler. The mud then contained in the water 35 is extraordinarily fine and mobile, and each small particle of water which is in the steam-space is the carrier of a small quantity of sediment or mud. The steam thus rendered impure passes in the case of well- 40 known steam generators directly into the superheater where also particles of water which float in the steam are converted into steam. The fine particles of sediment which have been carried in by means of the wet 45 steam are converted in the superheater into a fine, very light dust which is carried by the superheated steam to the place of consumption where it gives rise to disturbances or breakdowns. In the case of condensing 50 steam turbines in particular does such im-

pure steam cause disturbances, since in the low pressure parts of the turbine condensation frequently occurs even on the blades, and the dry dust aided by the centrifugal action of the running blade remains adhering to the wet blades of the running wheel or of the guide-wheel.

The object of the invention is to free, in the boiler itself, from the above-mentioned fine sediment the wet steam generated in a steam boiler of any construction whatever before it leaves the boiler, that is, before it passes into the superheater and reaches the place of consumption. For this purpose there are inserted in the steam-space of the 60 boiler walls which are provided with openings, and which dip into the water and which divide the steam into as many thin layers or currents, as possible, which flow preferably in varying directions past the adhesion surfaces furnished by the walls. The total cross-sectional area of the passage through the walls suitably amounts to a 65 multiple of the cross-sectional area of the steam delivery union opening beyond the 70 walls in order that the steam may flow at a suitable velocity along the adhesion-surfaces. All the particles of water contained in the steam flowing along the adhesion-surfaces 75 adhere to the latter, and said particles as mentioned above carry the mud particles along with them, so that said mud particles also become deposited on the adhesion-surfaces and flow back into the boiler water together with the water which has adhered to 80 said surfaces. The steam which has passed the surfaces is free from all impurities and is delivered at some point beyond the adhesion-surfaces. In order that the steam 85 may not become impure again no steam is intended to be generated in that part of the steam-space which is situated beyond the adhesion-surfaces. In order to assure this, the walls dipping into the water are arranged at such a place that a chamber 90 separated from the remainder of the steam-space is formed by the said walls, which chamber is situated in a part of the boiler which is exposed to the furnace gases either not at all 95 or only to such a slight extent that steam is 100

not generated in it. The steam delivery union is connected to this chamber which is separated from the rest of the steam-space. Consequently no steam can be delivered 5 which has not passed the adhesion-surfaces, that is, which has not been cleaned. Steam can be prevented from being generated in the separated chamber also by arranging for the feed-water which is at a temperature below 10 the temperature of vaporization to enter into the part of the boiler which is situated beyond the adhesion-surfaces.

In the drawing one form of the new device is represented diagrammatically by way 15 of example.

In said drawing: Figure 1 is a longitudinal section through the steam-space of a steam generator provided with the new device and Fig. 2 is a transverse section. Figs. 20 3 to 6 show to an enlarged scale various forms of the walls which furnish the adhesion-surfaces and which dip into the water.

a is, for example, the upper drum of a 25 steam generator. Into the front part of the upper drum *a* there opens the pipe *b* in which flows the ascending portion of the circulating current, while the water returns at *c*, for example. The two pipes *b* and *c* may 30 be connected with the top ends of a vaporizer of any known type provided with water-tubes or fire-tubes, or be connected with a lower drum of any well-known construction. At the back part of the upper drum *a* 35 the walls *d* are built in, which reach down to such a distance that they dip into the water in the boiler even when at its lowest level. By means of the walls *d* a chamber *D'* is divided off from the steam-space *D* in 40 the back part of the boiler which is exposed to the furnace gases either not at all or only to a slight extent, to which chamber the steam outlet-union *e* is connected. The apparatus may also be so arranged that in case 45 the construction of the boiler renders it desirable, the walls *d* are inserted in the front part of the upper drum. The walls *d*, however, are always so situated that if one imagines oneself to travel in the direction in 50 which the steam flows, they are reached before the outlet for the steam.

The walls *d* which divide the steam into many thin layers or currents and which furnish the adhesion-surfaces, may, as shown 55 in Fig. 3 or 4 consist of several rows of angle-irons *f* or *g* which are staggered relatively to one another in order to alter the directions of the individual currents of steam. The total cross-sectional area of the 60 passage through the angle-irons *f* is a suitable multiple of the cross-sectional area of the outlet-union *e*. The walls may, however, as shown in Fig. 5 consist of a row of zig-zag-shaped plates *h* arranged side by side,

or, as shown in Fig. 6, of several rows of semi-circular plates *i* staggered relatively to one another. They may, however, also be formed in any other suitable manner.

I claim:—

1. In a steam generator including a suitable drum: a plurality of walls located in said drum and providing adhesion surfaces for the particles of water carried by the steam and the solid matter contained therein, said walls dipping into the water in the 75 drum and dividing the same into two chambers, the steam being generated in one chamber and passing through said walls into the other wherein no steam is generated and from which the steam generated in the first 80 named chamber is removed.

2. In a steam generator including a suitable drum: a plurality of walls located in said drum and providing adhesion surfaces for the particles of water carried by the 85 steam and the solid matter contained therein, said walls dipping into the water in the drum and dividing the same into two chambers, the steam being generated in one chamber and passing through said walls into the 90 other which is located in the portion of the boiler substantially unexposed to the furnace gases and from which chamber the steam generated in the first named chamber is removed.

3. In a steam generator including a suitable drum provided with a steam outlet: a plurality of walls provided with passages, of a total cross sectional area which is a multiple of the area of said steam outlet, located 100 in said drum and providing adhesion surfaces for the particles of water carried by the steam and the solid matter contained therein, said walls dipping into the water in the drum and dividing the same into two chambers, the steam being generated in one chamber and passing through said walls into the 105 other wherein no steam is generated and from which the steam generated in the first named chamber is removed.

4. In a steam generator including a suitable drum: baffles consisting of a plurality of rows of members of suitable shape providing adhesion surfaces for the particles of water carried by the steam and the solid 115 matter contained therein, the members of the respective rows being staggered relatively to one another and dipping into the water in the drum and dividing the same into two chambers, the steam being generated in one 120 chamber and passing through said walls into the other wherein no steam is generated and from which the steam generated in the first named chamber is removed.

5. In a steam generator including a suitable drum: baffles consisting of a plurality of rows of angle irons providing adhesion surfaces for the particles of water carried

by the steam and the solid matter contained therein, the said angle irons of the respective rows being staggered relatively to one another and dipping into the water in the 5 drum and dividing the same into two chambers, the steam being generated in one chamber and passing through said walls into the other wherein no steam is generated and

from which the steam generated in the first named chamber is removed. ¹⁰

In witness whereof I have hereunto set my hand in presence of two witnesses.
